UNITED STATES PATENT OFFICE.

NICOLAS ARTHUR HELMER, OF CINCINNATI, OHIO.

SEPARATING DEVICE.

1,304,681.

Specification of Letters Patent. Patented May 27, 1919.

Application filed April 25, 1918. Serial No. 230,656.

To all whom it may concern:

Be it known that I, NICOLAS ARTHUR HELMER, a citizen of the United States, and a resident of Cincinnati, county of Hamilton, State of Ohio, have invented a certain new and useful Improvement in Separating Devices, of which the following is a specification.

My invention relates to separating devices 10 and more particularly to separating devices for evaporators and stills.

In evaporating liquids such as, for instance, sugar solutions, milk, oils, etc., and in the fractional distillation of oils, ethers, 15 alcohols, etc., it is generally desirable or even necessary, in order, for instance, to conserve the material from entrainment losses or to prevent the pollution of the escaping vapors, to provide some means for preventing any 20 minute particles from being carried over with the vapors.

The operations, in many cases, are conducted under conditions where the impedance of the passage of the vapors will be 25 prejudicial to the operation of the process or to the capacity of the apparatus, by reason of the increase in the pressure required to cause the proper rate of flow of the disengaged vapors due, for instance, to the resistance caused by sharply diverting the path 30 of said vapors or because of the adherence in the passages of scale or coatings from the material itself. This is particularly objectionable, in vacuum apparatus because of the 35 small range of pressure commonly encountered, especially in the case of multiple effect evaporation. For the reason last expressed, it is also particularly desirable to prevent the loss of heat by radiation.

40 The object of my invention is to provide a construction in which the objectionable features recited above, as well as others, are obviated and which is simple and economical in arrangement and operation and of maximum efficiency. Other more specific objects 45 will appear in the description hereinafter and the features of novelty will be pointed out in the appended claims.

In the accompanying drawings, Figure 1 50 is a diagrammatic view, partly in section, of

an apparatus used in the manufacture of sugar with my invention operatively combined therewith; Fig. 2 is a detail sectional view of my invention on an enlarged scale, taken on the line 2—2 of Fig. 3; Fig. 3 is 55 a horizontal section on the line 3—3 of Fig. 2; Fig. 4 is a sectional view on the line 4—4 of Fig. 3; Fig. 5 is a plan view; and Figs. 6 and 7 are detail perspective views; it is to be distinctly understood that the apparatus 60 shown in the drawings has been chosen simply for the purpose of illustrating and describing my invention and for no other reason.

As shown in Fig. 1, the apparatus diagrammatically illustrated comprises a series 65 of evaporators, 5, of any well known or suitable construction and connected with each other by pipes, 6, extending from the upper end of one evaporator to the lower end portion of the next adjacent evaporator. The apparatus may include any and all features 70 usually found in apparatus of the type in question and has been shown in a diagrammatic form, in the drawings, as the details 75 of said apparatus, other than those forming part of my invention, are of no consequence.

At a point between the inlet and outlet and preferably in close proximity to the inlet ends of the pipes, 6, each evaporator is 80 provided with my improvement, which in its illustrated form, comprises a bottom plate, 7, having its inner surface preferably converging downwardly toward an opening, 8, located, for instance, at the central point 85 of said plate 7. The inner surface of the latter may further be provided or formed with an outer series of bosses, 9, located along the periphery of said plate, 7, with their opposed ends spaced from each other; 90 a similar inner series of curved bosses, 10, with their opposed ends also spaced from each other, are located within the bosses, 9, on the plate, 7, the horizontal upper surfaces of the inner bosses, 10, being preferably in a 95 lower plane than the corresponding surfaces of the outer bosses 9.

In its illustrated form, my invention further includes outer segmental members, 11, and inner segmental members, 12, the mem- 100

bers, 11, being provided preferably at a point intermediate of their edges with relatively longer ribs, 13, located between two relatively shorter ribs, 14, said ribs all extending lengthwise of the members, 11, along the inner concave surfaces thereof. The inner members, 12, are provided with single ribs, 15, extending lengthwise thereof along their outer convex surfaces, as shown 10 in Fig. 3.

The outer segmental members, 11, in the assembled condition of the parts, are secured, in upright positions, upon the outer bosses, 9, in any suitable manner as, for instance, by means of bolts, 16, which pass through flanges, 17, located at the lower ends of said members, 11; similarly, the inner segmental members, 12, are fastened, in upright positions, upon the inner bosses, 10, 20 in any suitable manner as by means of bolts, 18, which pass through flanges, 19, located at the lower ends of said members, 12.

When in position upon the respective bosses, 9 and 10, the members 11 and 12, 25 with the illustrated arrangement are staggered with respect to each other and the inner members, 12, form a series within the series of outer members, the opposed upright edges of the members in each series being spaced apart to form spaces 20 and 21, the purpose of which will be more clearly pointed out hereinafter. As shown in Fig. 3, the ribs 13 and 14 of the outer members 11 are located opposite to the spaces 21 between adjacent inner members, 12, while the ribs, 15, of the inner members 12 are located 35 in registry with the spaces 20 between adjacent outer members, 11.

The construction further includes a top 40 plate, 22, which may be in the nature of an annular member fastened to the upper ends of the members 11 and 12 in any suitable manner as by means of bolts 23 passing through flanges 24 and 25 located, respectively, at the upper ends of said members 11 and 12. The top plate, 22, closes the upper end of the annular space between the series 45 of outer members 11 and the series of inner members 12 and leaves the interior space 26 within the series of inner members upwardly open for communication with the pipes 6. As illustrated in Fig. 3, wire cloth or similar material is secured along opposite vertical edges of each outer member 11 and passes 50 over and is preferably secured to the ribs 13 and 14 thereof to form foraminated walls 27 and 28; in the same way, wire cloth or the like is secured to the opposite vertical edges of each inner member 12 and passes 55 over and is preferably secured to the flange 15 thereof to form foraminated walls 29.

The foraminated walls, 27, 28, and 29, extend substantially throughout the upright length of the members 11 and 12 and together form channels 30 which communicate

with the interior of the evaporator through the spaces 20 and with the interior space 26 and pipes 6 through the spaces 21.

The construction described thus comprises a cylindrical element provided with lengthwise extending openings 20 and 21 with an upwardly open interior space 26 and with interior channels 30 having foraminated walls 27, 28 and 29, the latter being preferably arranged in a manner to cause each channel 75 to extend in at least two directions at an angle to each other. It will, of course, be understood that this specific embodiment of my invention is only an example and that the construction and arrangement may be 80 varied to meet the requirements of each case without in any way affecting the efficiency of my improvement.

In the illustrated example, the vaporization process being carried out in the vaporizers 5 in the customary manner, the vapors will eventually pass from one vaporizer to the next through the pipes 6. However, before each pipe 6 is reached the vapors travel inwardly through the spaces or openings 20 and along the channels 30 between and in contact with the foraminated walls, 27 and 29, and along and in contact with the foraminated walls 28, whereby the direction of flow of said vapors is changed and 95 they are caused to impact against said walls, 28, and finally pass inwardly through the spaces or openings, 21, to the interior space, 26, from which they leave the particular evaporator, 5, through the connecting pipe 100 6 and pass to the next adjacent evaporator, 5, where the same operation is repeated.

In contacting with the foraminated walls, 27, 28 and 29, some part of any fluid carried along by the vapors will be retained by 105 said walls, for instance, in the form of small drops or particles which become caught in the foramina of the woven fabric or the like. As the process continues, the capillary attraction which the retained particles of 110 fluid have for any other minute particles of the same fluid which may touch them as the vapors pass along will cause additional fluid to be collected upon the foraminated walls, 27, 28, and 29. Successive minute 115 particles of fluid will in this way be consolidated into larger quantities, out of the path of the vapors, of such size or mass as to prevent them from being again caught up and carried along by said vapors. As 120 the collected liquid is thus consolidated it will finally drop from the foraminated walls, 27, 28 and 29, to the bottom plate 7, and pass back therefrom into the evaporator 5 through the opening 8.

It will be seen that the vapors are not forced through the wire fabric or other foraminated material but are caused to travel along the foraminated walls in contact therewith and by having their direc- 125 130

tion of flow changed are impacted against the foraminated walls, 28, the whole arrangement avoiding any impedance to the passage of said vapors. At the same time 5 the fluids, carried along by said vapors, are removed therefrom in an efficient manner through said contact with the foraminated walls and without interfering in any way with the capacity or economy of operation 10 of the apparatus.

In all cases the invention in question provides areas which are ample for the passage of the vapors and in addition the construction and design is such that a modification 15 thereof is readily possible whereby an increase in area is easily effected when necessary or desirable. A maximum of efficiency is acquired by providing a relatively narrow path for the vapors which 20 are thus thinned or spread out as it were to expose the greatest possible area thereof to the action of the woven fabric or the like.

It will be readily apparent that my invention may be efficiently used in many ways other than the one illustrated and described; it is to be further understood that various changes in the specific form shown and described may be made within the scope 30 of the claims without departing from the spirit of my invention.

I claim:

1. The process of separating fluids from vapors which consists in passing the vapors 35 along a foraminated member in surface contact therewith, but not through said member.

2. The process of separating fluids from vapors which consists in passing the vapors between and along foraminated members in 40 surface contact with the opposed surfaces thereof but not through said members.

3. The process of separating fluids from liquids which consists in causing said vapors to impact against and travel along but not 45 through a foraminated member by changing the direction of flow of said vapors.

4. The process of separating fluids from vapors which consists in collecting particles of fluids from the vapor on a foraminated 50 surface, and passing subsequent vapors in a stream along and in contact with said foraminated surface and the collected particles thereon whereby the latter collect additional particles of fluid by capillary attraction.

5. In a separator of the kind described, a conduit for vapors including a foraminated member and means for producing a flow of vapors along said foraminated member but not through the same.

6. In a separator of the kind described, a conduit for vapors including opposed foraminated members forming a channel and means for producing a flow of vapors through said channel and along said foraminated members but not through the same.

7. In a separator of the kind described, a conduit for vapors including opposed foraminated members forming a channel and means for producing a flow of vapors through said channel and along said foraminated members but not through the same, 70 said channel having contiguous portions extending at an angle to each other whereby the direction of flow of said vapors is changed and said vapors are impacted 75 against some of said members.

8. A separator of the kind described comprising a device having an interior channel provided with an inlet and an outlet, foraminated walls extending along said channel between said inlet and outlet and means for producing a flow of vapors through said channel and along said foraminated walls 80 but not through the same.

9. A separator of the kind described comprising a device having an interior channel provided with a plurality of inlets and outlets staggered relatively to each other and foraminated members extending along said channel and forming the walls between said 90 inlets and outlets along which vapors pass in surface contact.

10. A separator comprising a bottom member, a top member, upright members located between said bottom and top members 95 and spaced apart to form an interior channel having inlets and outlets and foraminated members within said channel and forming opposite walls along which vapors pass in surface contact.

100 11. A separator comprising opposite end members, two series of members between said end members spaced apart to form a channel and spaced apart at opposed edges to form inlets and outlets to and from said 105 channel, ribs extending lengthwise of said members and projecting into said channel and foraminated sheets connected with each member and extending over said flanges to form foraminated wall in said channel along 110 which the vapors flow in surface contact.

115 12. A separator comprising an end member, two series of bosses located within each other on said member in different planes and in staggered relation to each other, two series of members spaced apart to form a channel and having one end secured to said bosses, members in each series being spaced apart at their opposed edges to form openings staggered relatively to each other, a second end 120 member secured to the opposite end of said two series of members to close the space therebetween, single ribs extending outwardly from the members of the inner series at intermediate points thereof, a trio of ribs 125 extending inwardly from the members of the outer series at intermediate points thereof, and sheets of foraminated material secured along the opposite longitudinal edges of the members in each series and extending over 130

and in contact with the ribs of said members to form foraminated walls along which vapors flow in surface contact.

13. The combination of an evaporator or 5 still having an outlet and a separator located inferiorly at said outlet, said separator comprising a bottom member, a top member, upright members located between said bottom

and top members and spaced apart to form an interior channel communicating with said 10 inlet and outlet and foraminated members within said channel forming opposite walls along which vapors pass in surface contact.

In testimony whereof I have hereunto set my hand.

NICOLAS ARTHUR HELMER.
